SELF-CONTROLLED TORPEDO

Luis Alberto Villafuerte Rozas, Cuzco, Peru

Application December 20, 1946, Serial No. 717,462

5 Claims. (Cl. 114—21)

1

My present invention relates to the general class of marine torpedoes, and more specifically to a self-controlled torpedo which is provided with a mechanical steering appliance automatically operated by the actuation of electromagnetic mechanism under the influence of electrical impulses from a metal surface-ship or similar target when the torpedo reaches a predetermined proximity with relation to the target.

In carrying out my invention I employ within the nose of the torpedo a swiveled electro-magnetic control needle or pointer, which is energized, after the torpedo travels a predetermined distance, and activated to transmit motion and power, through electro-magnetic and mechanical means, to the steering appliance of the torpedo, which includes an exterior rudder.

The control needle within the interior of the torpedo is located preferably in its nose or point and alined with the exterior rudder at the stern of the torpedo, and the needle and rudder are initially alined with the longitudinal axis of the torpedo.

If the magnetic target is stationary, or if the target-ship is proceeding on an even or straight course, the torpedo, under control of the needle or pointer, is automatically directed to the target; in the event the target-ship zig-zags, or changes its course, the swiveled control needle or pointer changes its position to follow the target, and the rudder is consequently steered to alter the course of the torpedo and direct it to its target.

The invention consists essentially in certain novel combinations and arrangements of parts involving the above features and functions as will hereinafter be described, and more specifically pointed out in my appended claims.

In the accompanying drawings I have illustrated so much of a torpedo as is necessary to disclose one complete example of the physical embodiment of my invention, wherein the parts are combined and arranged in accord with one mode I have devised for the practical application of the principles of my invention.

It will be understood that changes and alterations in these exemplifying drawings and structures, and additional accessories may be added, within the scope of my appended claims, without departing from the principles of the invention.

Figure 1 is a horizontal sectional view of a portion of the hull of a torpedo in which my control mechanism is embodied, indicating the pointer and rudder alined with the longitudinal axis of the torpedo, as when the torpedo is proceeding on a straight and direct course toward its target.

Figure 2 is a vertical longitudinal sectional view of a portion of the hull of the torpedo, showing in side elevation and partial section the control mechanism of Fig. 1.

2

Figure 3 is a diagram of the electrical wiring system of the control mechanism.

Inasmuch as my invention relates only to the control mechanism for steering the torpedo, the propulsion mechanism, the explosive charge and its detonating mechanism, and other necessary accessories of the torpedo are omitted from the drawings and description. The hull 1 of the torpedo may be of conventional size and shape, and its exterior rudder 2 is mounted beneath its stern with the vertical stem 3 rising within the interior of the hull and journaled to turn in suitable bearings 4. The stem 3 is mechanically turned on its vertical axis through a driven segmental gear 5 mounted thereon that meshes with a pinion 6 the shaft 7 of which is journaled in bearings indicated at 8, rigid with the hull; and the pinion is actuated by means of a driving segmental gear 9 journaled with its shaft 10 mounted in bearings 11.

The driving segmental gear is oscillated to steer the rudder through the instrumentality of a longitudinally extending centrally mounted upright rectangular flexible control frame indicated as a whole by the numeral 12, which frame includes at its forward end a vertical link 13 that is held in upright position by pressure from a spring 14 mounted within the flexible frame.

At its rear end the flexible control frame is mounted on and supported by a shaft, as 10, to turn the shaft and swing or oscillate the driving segmental gear of the shaft 10, and thus control the rudder. The control frame is oscillated, through intermediate mechanisms, from the needle or pointer located at the bow or nose of the torpedo, as will be described.

As auxiliary manually operated means for initial adjustment of the rudder, a hand wheel 15 is mounted laterally of the driving segmental gear 9, and through the operation of a pinion 16 on its shaft 17, power and motion are transmitted to an arcuate rack 18. The rack is integral with a lever 19 having a stationary pivotal mount 20, and the lever is connected with the driving segmental gear 9 by a slot 21 of the lever and a pin 22 of the segmental rack 9.

The control frame 12 of the steering apparatus or unit is initially activated from the bow or nose of the torpedo under the influence of electrical impulses received from the metal target when the torpedo reaches a predetermined zone of electrical influence.

For initiating the required motion and transmission of power for operating the control frame, an electromagnetic pointer or needle 23, preferably located within the nose of the torpedo, is initially alined with the rudder on the longitudinal axis of the torpedo, and the electromagnetically produced oscillations of the pointer are

transmitted by motion and power through intermediate mechanisms, and reproduced or duplicated by the steering rudder.

For this purpose the electromagnetic needle 23 is wound with an exterior coil 24 receiving energy from a battery 24a, and the needle is swiveled for oscillations by means of a spindle 25 journaled in vertical position in bearings 26. The needle is provided with a rear extension or arm 27 of non-magnetic material, and this arm is equipped with a contact button or head 28 forming a movable contact that is adapted to frictionally and electrically engage, separately, with a series of stationary contacts 29 mounted upon the central arcuate portion 30 of a transverse frame rigid with the interior of the hull 1.

Each of the multi-contacts 29 is connected with a complementary group of stationary electromagnets or solenoids 31 which are supported in parallelism and disposed longitudinally of the torpedo in a supporting frame 32, and each solenoid is equipped with an axially aligned reciprocable core or armature 33. When the solenoid is energized the armature is attracted thereto for a working stroke, and when the solenoid is de-energized the armature is automatically and mechanically withdrawn from the solenoid on an idle stroke.

On its working stroke the armature is designed to initiate power and motion for actuating the steering frame 12 of the rudder, through the instrumentality of an initially inoperative reciprocable push or actuator bar 34, which is suspended, and slidably supported in a frame 35 below the plane of the solenoid and its armature. This working stroke of the armature is imparted to a vertically operating lifting device or elevator that raises the push bar into operative position, and then lowers the bar to inoperative position after its working stroke.

The elevator includes a lever 36 located beneath the plane of the armature, with its short arm loosely united with or operatively connected to a complementary arm or leg of a fixture 37 that is rigidly mounted on the armature and reciprocable therewith.

The long arm of the elevator-lever is equipped with a suspension loop 38 that loosely engages around and co-acts with the forward rack-end 39 of the push bar 34 to elevate or lift this end of the bar in order that the bar may bodily be projected rearwardly by rotary mechanism in co-action with the rack, as will be described.

As best seen in Fig. 1, each push bar 34 at its rear end terminates in a diagonal or biased arm 40 that extends obliquely across the longitudinal axis of the projectile and in position to co-act with the control frame for steering the rudder. Obviously, in its rearward plunge with the push bar, the arm 40 will contact with and frictionally engage the spring pressed link 13 of the control frame to operate the rudder.

If the needle swings to the port side in Fig. 1, the rudder also will turn to port; and conversely, if the needle swings to starboard, the rudder will be operated to steer the torpedo in that direction; and continued swinging movement of the swiveled movement in the same direction will cause successive operations of individual push bars in the group at the side opposite to the side-swing of the electromagnetic needle or pointer.

When the armature of one of the solenoids has been deenergized and the push bar controlled thereby has performed its required function, the elevator automatically lowers the push bar to

inoperative position in order that an idle stroke may be imparted to the reciprocable push bar to retract the cam arm 40 from operative relation with the control frame for the rudder. For this purpose a spring 41 at one end is attached at 42 to the push bar 34 and anchored at its other end to a portion of the fixed frame 35, for restoring the push bar to its initial normal position.

For separately and independently imparting the working stroke to each push bar after its forward end has been elevated to operative position, a multi-gearied rotary drum 43 which is provided with spaced gears 44, is journaled transversely of the torpedo in bearings 45. The group of gears includes one for each rack bar, and the drum is located above the push bars in order that the rack end 39 of a push bar may be lifted by the elevator into operative engagement with a drum-gear, while the drum is constantly revolving.

The rotary drum may be driven from the power plant of the propulsion mechanism of the torpedo, or by any other suitable means, as for instance an electric motor 46, and its belt drive that includes a driving pulley 47, belt 48, and the driven pulley 49 on the rotary drum.

For automatically controlling the electric operating circuit for the needle or pointer, the circuit which is indicated at 50, is provided with a circuit breaker 51 that is opened to demagnetize the solenoid after a working stroke of its push bar. The circuit breaker is opened by means under control of the resilient steering frame 12 when the cam arm 40 contacts with the spring pressed link 13 of the frame. By this contact the link is pushed rearwardly, and the upper bar 52 of the flexible frame which is pivotally connected to a transversely arranged lever 53 swings this lever on its pivot 54, and this movement of the lever projects forwardly a slidably supported cam-bar 55 that co-acts with the circuit breaker for opening the circuit.

In order to afford the needle an opportunity to assume a new position under influence of a possible variation in the course of the target-ship, lever 19 of the steering appliance imparts a limited rotary retarding movement through the hand wheel 15. This retarding movement of the hand wheel allows time for retraction of the spring pressed link 13 of the control frame and consequent closing of the switch 51. The control mechanism of the torpedo, therefore, actuates only in a comparatively close field around a target ship, and the operation may be described as operating with a plurality of impulses. The needle follows the target ship and through the solenoids moves the actuator bars rearwardly pushing the link 13 toward one side wherein the rudder is held at a slight angle. This action continues until the bar 55 opens the switch 51 and then the actuator bar continues to hold the rudder through the link 13 a short period of time, such as a few seconds, during which time the rudder influences the direction of the torpedo. As soon as the contact is broken the rudder and needle are released, and when released, the needle again instantly actuates the rudder through the same cycle.

For use in determining and governing the approximate point or distance in the course traveled by the torpedo at which the electromagnetic needle shall become operative; and also the estimated maximum duration of elapsed time for exploding the traveling torpedo, a governing screw bar 56 is disposed transversely of the torpedo above the rear end of the needle, and journaled in bearings 57.

The screw bar is revolved, at reduced speed, from the drum 43 through a system of intermediate pulley and belt drives designated as 58, 59, and 60.

To determine the distance at which the directional mechanism shall become operative, and with the screw bar rotating at a slow speed, the needle is held against swivel movement for a predetermined period of time by means of a previously set horizontally disposed safety lock 61 that is forked to straddle the rear end of the needle, and is pivoted at 62, in suitable bearings, between the swivel of the needle and the transverse screw bar.

The forked stop or safety lock is designed to swing away from engagement with the lever-end of the needle at the predetermined time and thus permit the needle to operate when it is energized.

For releasing the safety lock a lifter 63 having a slide sleeve 64 and mounted to slide transversely of the torpedo on a guide rod 65, is employed. The lifter is in the nature of a non-rotary threaded nut mounted on the screw bar and it is designed to travel across the screw bar inwardly toward the lock device as the screw bar slowly revolves.

At the terminus of its travel transversely of the torpedo the lifter contacts the safety lock and by frictional engagement therewith lifts the forked lock to release the needle.

A normally open electrical switch, indicated at 66 forms part of the electrical operating system of the torpedo, is designed at the predetermined time to detonate the explosive charge of the torpedo. The switch is located at the outer end of one of the threaded sections of the doubly-threaded screw bar, and the timing of this detonating switch is governed by the rotary movement of the screw bar in co-action with a timing switch-closer 67, which is a device of the same type as the lifter 63.

The closer 67 for the detonating switch, in the nature of a non-rotary traveling nut actuated by the screw bar is guided by its sleeve 68 on the guide rod 65, and the closer travels from the central portion of the screw bar, outwardly, toward the detonating switch which is located in its path of movement and is closed by engagement of the closer with the switch.

When the needle is released, and with electric currents emanating from the battery 24a, the needle is energized to establish communication with the target; and under increasing influence, as the torpedo approaches its target the needle is oriented toward the target; the contact button of the needle carries the battery charge to one of the group of stationary buttons, producing immediate induction in a solenoid, for initiating the steering operation of the torpedo.

As an example, the distance a ship or other objective is located from the ship sending the torpedo is determined by a telemeter or the like and the operating parts within the torpedo are set accordingly. The size and volume of the ship are taken into consideration and the field of induction most probable for subduing the northern terrestrial influence is determined, and taking these factors into consideration the needle is inclined toward the objective. It is desired that the needle be positioned on the longitudinal center of the torpedo but should the torpedo be driven from its course by wind or the like the needle will rotate about its pivot to point directly to the objective and in this movement the contact on the rear end of the needle will engage a contact of a

solenoid on either side of the center and the solenoid will actuate its push bar 34 and force the cam arm 40 into engagement with the post 13 of the frame 12 whereby the rudder is actuated to an inclined position opposite to that of the needle. As the needle continues to rotate about its axis the contacts of other solenoids are engaged and the position of the rudder is changed accordingly.

10 This action continues uninterruptedly with the needle rotating in a clockwise direction, however, when the needle rotates in a counterclockwise direction the circuits to the solenoids are continually interrupted by the circuit breaker 51 to correct the position of the needle. It is preferred to use the interrupted circuit on one side of the torpedo because with the torpedo traveling against the northern terrestrial influence it is necessary to correct the position thereof at comparatively short intervals. Torpedoes may be provided with the interrupted circuit in opposite sides depending upon directions in which the torpedo is started.

Having thus fully described my invention, what I claim as new and desire to secure by Letters Patent is:

1. In a torpedo steering unit, the combination which comprises a magnetically influenceable needle having a point on the forward end and a contact on the rear end pivotally mounted intermediate of the ends thereof in the forward end of the torpedo, a battery of solenoids in the torpedo spaced from the rear end of the needle and each of said solenoids having a contact positioned on a radius from the center of the pivot point of the needle and spaced to be engaged by the contact on the rear end of the needle, a plurality of push arms having V-shaped cam elements on the rear ends thereof and gear racks 30 on the forward ends slidably mounted in the torpedo, a plurality of pinions in said torpedo positioned to be engaged with the said gear racks, means actuating the said gear racks by the solenoids to engage the pinions for sliding the push arms rearwardly, resilient means actuating the said push arms forwardly, a post carried by a frame and positioned to be engaged by the said V-shaped cam elements of the push arms, means pivotally mounting the frame in the torpedo, a gear segment carried by the frame, a rudder carried by a vertically disposed stem journaled in the torpedo, and means rotating the stem of the rudder by the gear segment of the said frame.

2. In a torpedo steering unit, the combination which comprises a magnetically influenceable needle having a point on the forward end and a contact on the rear end pivotally mounted intermediate of the ends thereof in the forward end of the torpedo, a battery of solenoids in the torpedo spaced from the rear end of the needle and each of said solenoids having a contact positioned on a radius from the center of the pivot point of the needle and spaced to be engaged by the contact on the rear end of the needle, a plurality of push arms having V-shaped cam elements on the rear ends thereof and gear racks 40 on the forward ends slidably mounted in the torpedo, a plurality of pinions in said torpedo positioned to be engaged with the said gear racks, means actuating the said gear racks by the solenoids to engage the pinions for sliding the push arms rearwardly, resilient means actuating the said push arms forwardly, a post carried by a frame and positioned to be engaged by the said V-shaped cam elements of the push arms, means

pivotally mounting the frame in the torpedo, a gear segment carried by the frame, a rudder carried by a vertically disposed stem journaled in the torpedo, means rotating the stem of the rudder by the gear segment of the said frame, and means breaking the circuits to the solenoids when the needle is influenced in a counterclockwise direction.

3. In a torpedo steering unit, the combination which comprises a magnetically influenceable needle having a point on the forward end and a contact on the rear end pivotally mounted intermediate of the ends thereof in the forward end of the torpedo, a battery of solenoids in the torpedo spaced from the rear end of the needle and each of said solenoids having a contact positioned on a radius from the center of the pivot point of the needle and spaced to be engaged by the contact on the rear end of the needle, a plurality of push arms having V-shaped cam elements on the rear ends thereof and gear racks on the forward ends slidably mounted in the torpedo, a plurality of pinions in said torpedo positioned to be engaged with the said gear racks, means actuating the said gear racks by the solenoids to engage the pinions for sliding the push arms rearwardly, resilient means actuating the said push arms forwardly, a post carried by a frame and positioned to be engaged by the said V-shaped cam elements of the push arms, means pivotally mounting the frame in the torpedo, a gear segment carried by the frame, a rudder carried by a vertically disposed stem journaled in the torpedo, means rotating the stem of the rudder by the gear segment of the said frame, and means manually controlling the position of the rudder.

4. In a torpedo steering unit, the combination which comprises a magnetically influenceable needle having a point on the forward end and a contact on the rear end pivotally mounted intermediate of the ends thereof in the forward end of the torpedo, a battery of solenoids in the torpedo spaced from the rear end of the needle and each of said solenoids having a contact positioned on a radius from the center of the pivot point of the needle and spaced to be engaged by the contact on the rear end of the needle, a plurality of push arms having V-shaped cam elements on the rear ends thereof and gear racks on the forward ends slidably mounted in the torpedo, a plurality of pinions in said torpedo positioned to be engaged with the said gear racks, means actuating the said gear racks by the solenoids to engage the pinions for sliding the push arms rearwardly, resilient means actuating the said push arms forwardly, a post carried by a frame and positioned to be engaged by the said V-shaped cam elements of the push arms,

means pivotally mounting the frame in the torpedo, a gear segment carried by the frame, a rudder carried by a vertically disposed stem journaled in the torpedo, means rotating the stem of the rudder by the gear segment of the said frame, and means manually controlling the position of the rudder, said manual controlling means retarding the return movement of the rudder when the circuits to the solenoids are broken.

5. In a torpedo steering unit, the combination which comprises a magnetically influenceable needle having a point on the forward end and a contact on the rear end pivotally mounted intermediate of the ends thereof in the forward end of the torpedo, a battery of solenoids in the torpedo spaced from the rear end of the needle and each of said solenoids having a contact positioned on a radius from the center of the pivot point of the needle and spaced to be engaged by the contact on the rear end of the needle, a plurality of push arms having V-shaped cam elements on the rear ends thereof and gear racks on the forward ends slidably mounted in the torpedo, a plurality of pinions in said torpedo positioned to be engaged with the said gear racks, a motor positioned in the torpedo for actuating the pinions, a screw positioned in the torpedo, followers positioned to travel on the screw, contacts positioned to be engaged by the followers on the screw, means setting the followers on the screw to provide timing means for closing the contacts to explode the torpedo, means actuating the said gear racks by the solenoids to engage the pinions for sliding the push arms rearwardly, resilient means actuating the said push arms forwardly, a post carried by a frame and positioned to be engaged by the said V-shaped cam elements of the push arms, means pivotally mounting the frame in the torpedo, a gear segment carried by the frame, a rudder carried by a vertically disposed stem journaled in the torpedo, and means rotating the stem of the rudder by the gear segment of the said frame.
